Keayon & Keayon

UNITED STATES PATENT OFFICE.

CECIL B. RUSKAY, OF FAR ROCKAWAY, NEW YORK.

ASH RECEIVER.

Application filed April 7, 1925. Serial No. 21,262.

To all whom it may concern:

Be it known that I, CECIL B. RUSKAY, a citizen of the United States, and a resident of Far Rockaway, in the county of Queens 5 and State of New York, have invented certain new and useful Improvements in Ash Receivers, of which the following is a specification.

My invention relates to ash receivers.

10 It has for its particular object an improved type of such a receiver in which ashes, cigar and cigarette stumps and used matches, may be deposited in one of its chambers, and removed from that chamber 15 into another chamber by means which will act as a gate or closure between the two. In this way the first chamber may always be kept clear of such refuse, and the discarded smokers' remnants concealed from 20 view and the offensive odors arising therefrom shut off.

Another object is the provision of an ash receiver with a minimum of parts to accomplish the above ends, combined in compact and artistic form.

The device will be readily understood from the accompanying drawings, in which Figure 1 is a perspective view of my improved ash receiver, and Fig. 2 a vertical section thereof; Fig. 3 is a plan view of the upper receptacle detached, and Fig. 4 is a detail view.

Referring to the drawings, it will be seen that the receiver is made up of a lower 35 globular chamber 1, and an upper circular chamber 2, whose diameter is somewhat smaller than that of the lower chamber, the two being combined in any way desired. The upper chamber is roofed by cover 3, 40 and its bottom, 4, which is shown clearly in Fig. 3, serves as a cover for the lower chamber 1. Each of the covers 3 and 4 is cut away for substantially half its area, the cutaway portion of cover 3 being indicated by the numeral 5, and the cutaway portion of cover 4 being indicated by the numeral 6. The open or cutaway portion of each chamber is opposite the closed portion of the other chamber.

45 The shaft 7 to which is fixedly attached, as by rivets 8, the two-winged scraper 9, is mounted in the upper chamber so as to be rotatable therein. The upper end of the shaft is threaded to receive the knob 10, and its lower end, 11, is adapted to bear

and be freely movable in opening 12 in cover 4. A similar opening in register with 12, is of course located in cover 3 to receive the shaft. 13 and 14 are cigarette or cigar rests, which may be soldered to the receiver. 60

In use my device is utilized in the following way. Ashes, and the usual refuse of the smoker, are dropped through the receiving opening 5, and gradually accumulate on bottom 4 unless and until the scraper, by means of knob 10, is twirled to sweep them through exit opening 6 into the lower chamber 1. The scraper is then preferably placed crosswise of the receiver so as to close the opening to the lower chamber, and prevent 70 the emergence of the odors arising from its contents. In this way the upper chamber may always be kept clean and presentable.

It will be evident from the foregoing that I have devised a novel ash receiver which 75 has apparent advantages over any in the art now known to me, and one which, while very effective in carrying out its designed purpose, is free from the obnoxious features of other such receivers which must be 80 emptied promptly after use or remain in unsightly view.

While I have shown and described my invention in its preferred form, I do not limit myself to the exact details of construction therein, as various changes or modifications might be made without departing from the spirit of the invention or the scope of the claims appended hereto. For example, other means may be provided 85 for operating the scraper 9 and it may be arranged by a system of gears that the scraper will be operated by a downward pressure placed on the knob 10. Spring means may also be provided to return the 90 scraper to its normal position upon the release of the pressure on 10. As can be understood, numerous other means and devices may be provided for operating the scraper 9.

What I claim as new and desire to secure 100 by Letters Patent, is:

1. An ash receiver comprising two chambers, one above the other, each provided with an opening, the openings being out of register with each other, and means rotatable in one chamber for the removal of the contents thereof through the opening into the other. 105

2. In an ash receiver, the combination of two chambers, one above the other, each pro- 110

vided with an opening, the openings being out of register with each other, a scraper mounted in one of the chambers and rotatable therein, and a member attached to the scraper for the purpose of operating the same substantially as described.

3. In an ash receiver, the combination of two chambers, one above the other, each of the chambers having a closed and an open portion, the closed portion of the one being opposite the open portion of the other, a scraper rotatably mounted in the upper chamber and operable from without said chamber by a member attached to the scraper.

4. In an ash receiver, the combination of two chambers, one above the other, the roof of each of the chambers having a part that is closed and a part that is open, the closed part of the one being opposite the open part of the other, a shaft mounted in the upper chamber to which is fixedly attached a scraper, the scraper being rotatable in the upper chamber and adapted to move the contents thereof into the lower chamber through the opening into the same.

5. In an ash receiver, the combination of two chambers, one above the other, the cover of each of the chambers having a part that is closed and a part that is open, the closed part of the cover of the lower chamber being opposite the open part of the cover of the upper chamber, and the closed part of the latter being opposite the open part of the former, a shaft mounted in the upper

chamber and equipped with a scraper which is rotatable in the upper chamber, said scraper being dimensioned to make substantially close contact with the walls of said last mentioned chamber, and adapted to close one open part from the other, and a knob attached to said shaft externally of the receiver, substantially as and for the purpose set forth.

6. In an ash receiver, the combination of two chambers, one above the other, the cover of each of the chambers being provided with an opening, said openings being out of register with each other, and means movable in the upper chamber to remove the contents thereof to the lower chamber through the opening into the same.

7. In an ash receiver, the combination of two chambers, one above the other, the cover of each of the chambers being provided with an opening, said openings being out of register with each other, a scraper movable in the upper chamber, by a member attached to the same and operable from the exterior of the ash receiver, to remove the contents of said upper chamber into the lower chamber through the opening in the same, and so dimensioned as to be adapted to make substantially close contact with the walls of said upper chamber and to shut off the said openings one from the other.

In testimony whereof, I have signed my name to this specification.

CECIL B. RUSKAY.
